UNITED STATES PATENT OFFICE.

OLE ANDERSON, OF HAMMOND, INDIANA, ASSIGNOR OF ONE-HALF TO HJALMAR NILSSON, OF HAMMOND, INDIANA.

DESIGN FOR A WALL PANEL.

Application filed February 21, 1922. Serial No. 823. Term of patent 14 years.

To all whom it may concern:

Be it known that I, OLE ANDERSON, a citizen of the United States, residing at Hammond, in the county of Lake and State of Indiana, have invented a new, original, and ornamental Design for a Wall Panel, of which the following is a specification, reference being had therein to the accompanying drawings.

In the drawing:

Figure 1 is a perspective view of a wall panel used for interior decorative purposes, showing my new design.

Figure 2 is a top plan view of my design.

Figure 3 is a view in front elevation of the design, showing the indentation sockets.

I claim:

The ornamental design for a wall panel, as shown.

OLE ANDERSON.
